J. P. BECKER,
LOCK FOR AUTOMOBILES,
APPLICATION FILED JUNE 26, 1916.

1,224,258.

Fig. 1.

UNITED STATES PATENT OFFICE.

JOHN P. BECKER, OF ST. LOUIS, MISSOURI.

LOCK FOR AUTOMOBILES.

1,224,258.

Specification of Letters Patent.

Patented May 1, 1917.

Application filed June 26, 1916. Serial No. 105,923.

To all whom it may concern:

Be it known that I, JOHN P. BECKER, a citizen of the United States, residing at the city of St. Louis, State of Missouri, have invented a certain new and useful Improvement in Locks for Automobiles, of which the following is a specification, reference being had to the accompanying drawing, forming a part thereof.

10 This invention relates generally to locks and, more especially, to a certain new and useful improvement in locks particularly designed for use in connection with automobiles, the principal object of my present invention being to provide a comparatively simple, inexpensive, and readily and conveniently operable lock of the kind described having a bolt-member adapted to engage with the clutch-lever of the automobile to efficiently lock the same against actuation and thereby prevent unauthorized use of the automobile.

25 With the above and other objects in view, my invention resides in certain novel features of form, construction, arrangement, and combination of parts, all as will hereinafter be described and afterward pointed out in the claims.

30 In the accompanying drawing which illustrates my invention in preferred form,

Figure 1 is a fragmentary plan view of the chassis or frame and engine-hood of an automobile equipped with my invention;

35 Fig. 2 is a side elevational view of the same, with a portion of the automobile-body in longitudinal section;

Fig. 3 is an enlarged plan view of an automobile-lock embodying my invention;

40 Fig. 4 is a sectional view of the same on approximately the line 4—4, Fig. 5;

Fig. 5 is a front elevational view of the lock;

45 Fig. 6 is a transverse sectional view of the same on approximately the line 6—6, Fig. 4; and

Fig. 7 is a longitudinal sectional view of the same on approximately the line 7—7 Fig. 4.

Referring to the said drawing, in which 50 like reference characters refer to like parts throughout the several views, A indicates the chassis-frame, B the engine-hood, C the foot-board portion of the body, and D the pivoted clutch-lever of an automobile of usual form and construction. The foot or clutch-lever D operatively projects up-

wardly through a suitable slot, as at c, in foot-board C and is adapted, as is well known, to operatively connect the engine with, or disconnect the same from, the running-gear of the automobile, the engine and running-gear of the car being disconnected when the lever D is in what is known as neutral position. To efficiently and positively lock this lever D releasably in such 65 neutral position and thereby prevent unauthorized use or driving of the car, I have provided my new lock, which comprises a base-plate 1 provided with a projecting extension or bracket-arm 2 adapted to be suitably bolted or otherwise fixed, as at 3, to the frame A, plate 1 being rigidly positioned and supported beneath or under foot-board C to one side of slot c and in operative position relatively to pivoted clutch-lever D. 75

Bolted or otherwise fixed, as at 4, to and upon base-plate 1, is a chambered cover or housing-member comprising a top wall 5, side-walls 6—6, rear end wall 7, and front end wall 8, the base-plate 1 forming the bottom wall of the complete housing for the parts hereinafter described. 80

Housed within said cover-member and suitably fixed preferably to and upon the under side thereof, as seen in Fig. 6, is a 85 suitable lock 9 including a suitable preferably spring-projected latch 10 and a key-receiving portion 11 projecting upwardly through suitable registering apertures provided in said cover-member and foot-board C, as seen particularly in Fig. 2, so as to be conveniently accessible to a person within the body of the automobile for the insertion or removal of a suitable key E for actuating latch 10, against the tension of its projecting spring (not shown), to retracted or bolt-unlocking position. 90

Having their opposite ends suitably fixed in the front and rear walls of the cover-member and located within the chamber 1 thereof on opposite sides of said lock 9, is a pair of longitudinally extending rods 12—12. 95

Longitudinally slidable within the chamber of the cover-member and upon the base-plate 1, is a clutch-engaging bolt comprising a pair of spaced apart bars 13—13 rigidly connected by an approximately centrally disposed cross-plate 14, the front wall 8 of the cover-member being suitably cut 110 away or apertured as seen particularly in Fig. 5 to accommodate sliding movement of

the bolt relatively to the plate 1 and cover-member. Each of the bars 13 is provided at its inner end with a lateral extension or lug 15 suitably apertured to accommodate and 5 slidably fit upon the fixed rods 12, and at its outer end with an upwardly disposed projection 16 adapted to provide a hand or finger-grip for actuating said bolt to clutch-engaging or projected position relatively to 10 the housing-member.

Disposed on the fixed rods 12 between said bolt-extensions 15 and the front wall 8 of the cover-member are coiled springs or the like 17.

15 In operation or use, the said bolt is suitably engaged or grasped at its extensions 16, which also suitably project upwardly through a suitable slot provided in foot-board C, and pulled outwardly, against the 20 tension of said springs 17, to projected position relatively to the housing-member, said bolt when in such projected position engaging at the forward ends of its bars 13 upon opposite sides of the clutch-lever D, 25 as illustrated particularly in Fig. 1, and thereby preventing any pivoted movement of said lever; and on the bolt being pulled past the latch 10 in its said outward movement to engage the lever D, the latch 30 10, under the tension of its projecting spring, springs into engagement with said bolt at preferably one of its lugs or extensions 15, as seen particularly in Fig. 4, and thereby locks the bolt in its said projected or clutch-35 engaging position. On a key E being inserted into portion 11 of the lock 9 and latch 10 thereby actuated to retracted position against the tension of its projecting spring, bolt-bars 13 will be at once, under 40 the tension or pull of springs 17, retracted out of locking engagement with the lever D, when the lever D may be freely actuated to connect the engine with the running-gear of the car as may be desired.

45 My lock is comparatively simple in form and construction, may be readily operatively mounted upon an automobile, and serves to efficiently as described lock the lever D against actuation to prevent unauthorized 50 use of the car.

I am aware that minor changes in the form, construction, arrangement, and combination of the several parts of my new lock 55 may be made and substituted within the scope of the appended claims for those herein shown and described without departing from the nature and principle of my invention.

Having thus described my invention, what I claim and desire to secure by Letters Patent is:

1. In a device of the kind described; an inclosing housing, a lock including a latch movable wholly within said housing and a portion projecting exteriorly of said housing, said portion being adapted only to receive a key to actuate said latch, fixed rods disposed longitudinally wholly within said housing, a bolt slidable within the housing and having a bifurcated portion adapted, 60 when the bolt is in projected position relatively to the housing, to engage with a pivoted lever to lock the same against movement, said latch being adapted to engage with said bolt to releasably lock the same in 65 projected position, extensions on said bolt slidably fitting on said rods, and coiled springs disposed on said rods within the housing and engaging said bolt-extensions, 70 said springs being adapted to yieldingly retract said bolt from projected position on the disengagement of said latch from the bolt.

2. The combination with an automobile, including its frame and clutch-lever, of a bracket-arm fixed to said frame, a plate-member on said arm disposed in operative position relatively to said lever, a housing-member fixed to said plate-member, a lock including a latch movable wholly within said housing-member and a portion projecting exteriorly of said housing member, 80 said portion being adapted only to receive a key to actuate said latch, rods disposed longitudinally wholly within said housing-member with their ends fixed in opposite 85 walls thereof, a bolt slidable upon said plate-member and within the housing-member and having a bifurcated portion adapted, when the bolt is in projected position relatively to the housing-member, to engage with said lever to lock the same against movement, said latch being adapted to engage with said bolt to releasably lock the same in projected 90 position, perforated extensions on said bolt slidably fitting on said rods, coiled springs 95 interposed on said rods between said extensions and a wall of said housing-member, said springs being adapted to yieldingly retract said bolt from projected position on the disengagement of said latch from the bolt, 100 and projections on the bifurcated portion of said bolt for actuating the same to projected position.

In testimony whereof, I have signed my name to this specification.

JOHN P. BECKER.
